UNITED STATES PATENT OFFICE

106,552

DESIGN FOR A DISPLAY STAND OR SIMILAR ARTICLE

William B. West, Canajoharie, N. Y., assignor to Beech-Nut Packing Company, Canajoharie,
N. Y., a corporation of New York

Application March 6, 1937, Serial No. 68,052

Term of patent 14 years

To all whom it may concern:

Be it known that I, William B. West, a citizen of the United States, residing at Canajoharie, county of Montgomery, State of New York, have invented a new, original, and ornamental Design for a Display Stand or Similar Article, of which the following is a specification, reference being had to the accompanying drawing, forming a part thereof, in which:

Figure 1 is a view in perspective of the article showing my design; and Figure 2 is a side elevation.

I claim:

The ornamental design for a display stand or similar article, as shown.

WILLIAM B. WEST.
